COMB OR THE LIKE

Harry C. Richards, Morristown, N. J., assignor to Foster Grant Co., Inc., Leominster, Mass., a corporation of Massachusetts

Application May 11, 1950, Serial No. 9,870

Term of patent 14 years

(CL. D86—8)

To all whom it may concern:

Be it known that I, Harry C. Richards, a citizen of the United States, residing at Morristown, in the county of Morris, State of New Jersey, have invented a new, original, and ornamental Design for a Comb or the like, of which the following is a specification, reference being had to the accompanying drawings, forming part thereof, in which:

I claim:

The ornamental design for a comb or the like, substantially as shown.

HARRY C. RICHARDS.
